UNITED STATES PATENT OFFICE.

RAYMOND MICHAEL SCHUTZ, OF ROCK VALLEY, IOWA.

DESIGN FOR A BADGE.

Application filed August 4, 1927. Serial No. 23,001. Term of patent 14 years.

To all whom it may concern:

Be it known that I, RAYMOND MICHAEL SCHUTZ, a citizen of the United States, residing at Rock Valley, in the county of Sioux and State of Iowa, have invented a new, original, and ornamental Design for a Badge, of which the following is a specification, reference being had to the accompanying drawing, forming part thereof.

I claim:

The ornamental design for a badge, as shown.

RAYMOND MICHAEL SCHUTZ.
